UNITED STATES PATENT OFFICE

103,120

DESIGN FOR A BOTTLE OR SIMILAR CONTAINER

Yasuhisa Mogi, New York, N. Y., assignor to Maison Joubert, Inc., New York, N. Y., a corporation of New York

Application December 18, 1936, Serial No. 66,620

Term of patent 14 years

To all whom it may concern:

Be it known that I, Yasuhisa Mogi, a citizen of Japan, residing at New York city, in the county of New York, Borough of Manhattan, and State of New York, have invented a new, original, and ornamental Design for a Bottle or Similar Container, of which the following is a specification, reference being had to the accompanying drawing, forming a part thereof.

I claim:

The ornamental design for a bottle or similar container as shown.

YASUHISA MOGI.
